MEANS FOR LOWERING A CONSTRUCTION
WITH A COMPARATIVELY LARGE BASE
INTO THE SOILBernardus Hermanus Henricus Zweers, Naarden,
Netherlands; vested in the Alien Property Cus-
todianApplication July 31, 1940, Serial No. 348,940
In Germany August 8, 1939

12 Claims. (Cl. 61—42)

The invention relates to the lowering into soil up to the required depth of foundational constructions which have been previously constructed in their entirety or in part—as for example the section of a tunnel, a quay foundation, or any foundational construction in general with a comparatively large basic surface—by means of washing away the supporting soil.

The lowering of piles and sheet pilings according to the jetting method whereby by means of a spouting jet the resistance of the soil is so diminished that the pile or sheet can be introduced into the soil through its own weight or by loading, for example with the help of a drop hammer—is well known and in general use.

The invention, however, relates to the lowering of a foundational construction with a comparatively large basic surface into the soil up to the required depth, and is particularly effective when an even distribution of pressure over the underlying soil is of major importance.

The soil may be excavated, for example to within one meter of the required depth and is as far as possible flattened. Then the foundational construction is placed and lowered into position, or is wholly or partly constructed on the spot. Thereafter a liquid is led under the construction in supply pipes that have been previously provided. If this is properly done, the sand will be washed away allowing the construction to sink.

Such a method, however, requires special precautions, since irregularities in the previously flattened soil cannot always be avoided, especially when the flattening has to be done under water, and moreover since soil is not, as a rule, homogeneous, an unequally distributed pressure is usually inevitable, causing very great extra strain to the foundation, as for instance in the case of a very long tunnel section. Besides, if the liquid were then to be supplied, there would be the difficulty that the water would flow along quite irregular paths of the least resistance which cannot be ascertained beforehand, so that the soil would not be washed away evenly over the whole surface. Consequently, the right position and an even pressure for the construction on the soil would not be obtained.

Therefore, according to the invention ribs, preferably with a triangular cross section, are fixed to the base of the construction. When a foundational construction provided with such ribs is lowered on to soil that has been previously flattened or dredged, these ribs penetrate the soil

to a certain depth. Hereby the immediate advantage is gained, namely that the pressure of the construction is much more evenly distributed over the underlying soil surface; eventual irregularities in the soil now exercise far less influence on the distribution of pressure, so that there is less likelihood of extra strain in the construction.

When the ribs do not completely penetrate 10 into the soil—which is entirely a matter of adjusting the form and the distances between each rib to the weight of the construction and the substance of the soil—channels are formed by the ribs and the surface of the soil. If liquid is now led under the foundation it will find an outlet 15 in these channels. When the velocity of the liquid is sufficiently high, soil will be carried away by it. Such displacement of the topmost layer of soil between the penetrating ribs causes an increase in the pressure per surface unit of soil; equilibrium is consequently disturbed, and the construction sinks until a new equilibrium has been obtained. This process generally takes place 20 continuously, and is carried on until the required depth has been reached.

Since, the ribs, and consequently also the channels limited by them are regularly distributed over the whole of the base of the construction, and since the liquid generally flows through all the 25 channels simultaneously, uniform penetration and almost the same soil pressure is obtained all over.

Moreover, to ensure that pressure is evenly distributed along the whole length of a rib, the 30 removal of soil from the channel itself can be effected regularly. The further one gets from the beginning of the channel, the greater will be the velocity of the liquid required to transport the soil. This determines the width of the channels which can be ascertained by experiment. The necessary decrease in their widths may be obtained by filling them up at the top, increasing 35 towards the direction in which the liquid flows. The velocity of the liquid therefore increases towards the ends.

It is also advisable to take steps to ensure that the stream of the liquid is properly directed into the channels, and that it is as free as possible 40 from strong or mutually very different eddies, e. g. in each channel a number of stream directors may be placed parallel to the length of the channel.

By dividing the number of ribs into at least 45 3 groups to which the liquid can be supplied in-

dependently (Figs. 1-5), the foundation can be lowered as desired; and even the stream of liquid for each channel can be regulated.

For the application of the above invention it is desirable to have fairly homogeneous soil which can be easily washed by the liquid. Less convenient soil may be replaced in advance by one that is more suitable, e. g., by sand.

To avoid subsequent sinking caused by further penetration of the ribs owing to great loads, the pressure on the soil during or immediately after the penetration of the ribs may be increased beyond the maximum that the building is expected to weigh on completion. In addition the channels as well as the spaces adjoining the sides of the foundation may be filled up, for instance with concrete.

The liquid can be led from an axial rib to both sides by means of channels. But this can also be done from one, or from two opposite sides of the foundational construction, whereby in the first case all channels end on one side, and in the second case alternatively on opposite sides.

If an axial rib is applied, by making the ribs on the one side opposite the channels on the other side of said axial rib (Figs. 6 and 7), and by arranging that most of the liquid for the one channel is supplied from the opposite rib on the other side of the axial rib, the width of this axial rib may be decreased.

The invention also includes within its scope constructions which can be sunk into the soil according to this method and furthermore a separate supporting plate (Figs. 6 and 7) provided with ribs which may be substituted for the specially made lower portion of the construction, and on which therefore the construction can be placed.

In the accompanying drawings these embodiments of the invention are illustrated, embodying the principal features of this invention.

Fig. 1 shows a cross section of a concrete block with two adjoining tunnel traffic roads;

Fig. 2 shows part of the vertical section along the line II-II of Fig. 1;

Fig. 3 is a horizontal sectional detail view taken along the line III-III of Fig. 1;

Fig. 4 is a bottom plan view of Fig. 1;

Fig. 5 is a sectional view through a slightly modified form of the invention;

Fig. 6 is a sectional view through another modified form of the invention;

Fig. 7 is a bottom plan view of Fig. 6.

At the bottom of the tunnel in the drawings there is a lengthwise axial rib 2 of which the cross section is a triangle with its base uppermost, and from which axial ribs 3 with the same triangular cross section extend transversely to both sides of the tunnel, forming channels 4 between them.

By employing a filling in the upper portion of each channel 4 (Figs. 2 and 4), the cross sectional areas of the channels are diminished from the center toward the outer ends. Experiments have shown that thereby the soil 6, which owing to the weight of the construction 1, partly presses into channels 4. The channels are thus formed into tubular passageways, so that the soil will be evenly carried away when liquid flows through the passageways.

From the axial rib 2 by means of a partition 8 and stream directors 9 the liquid supplied to channels 14, 15, 16 and 17, by tubes 7, is caused to flow outwards to both sides through the chan-

nels 4 as indicated by the arrows. An additional supply nozzle is shown by 10 in Fig. 5.

The lower portion of the tunnel (Fig. 5) may be a separate supporting plate 11 provided with ribs 11a fitting in notches 1b of superstructure 1a. Ribs 11a and notches 1b are provided to keep the superstructure in correct position on the supporting plate.

When the superstructure and specially constructed lower portion form a unitary structure as shown in Fig. 1, the tubes may be arranged in the middle as indicated by 7, but when a separate supporting plate is provided it is preferable to connect the pipes 7 at the sides as shown in Fig. 5.

According to Figs. 3 and 4 there is a cross partition 13 dividing the channels into four groups 14, 15, 16 and 17. For example, if the rear or the right side of the construction should sink too far, less or no liquid at all is supplied to the groups 14-15 and 15-16 respectively.

In Figs. 6 and 7 another modification is shown wherein the superstructure 1a is mounted upon a separate plate 11c having a centrally disposed rib 20 and a plurality of transversely disposed ribs 21 extending outwardly from the center rib thereby forming channels 22 therebetween, which channels are similar to channels 4 previously described. The ribs 21 on one side of centrally disposed rib 20 are placed opposite the channels 22 on the other side of rib 20, and the liquid for each channel 22 is supplied from a conduit 23 in a rib 21 on the opposite side of the central rib 20.

Having now particularly described and ascertained the nature of said invention and the manner in which it can be performed, I declare that what I claim is:

1. In combination, a tunnel section, foundation-al construction supporting plate or other three-dimensional construction with a large basic surface, a plurality of substantially parallel spaced ribs formed on the underside and extending to the edge of said surface thereby forming intermediate spaced channels between said ribs of substantial depth at said edge, said ribs adapted to cooperate with the earth to form tubular passageways extending to the edge of said basic surface, and means for directing liquid longitudinally through said passageways in order to wash laterally away the earth from under said construction.

2. In combination, a tunnel section, foundation-al construction supporting plate or other three-dimensional construction with a large basic surface, a plurality of substantially flush-top spaced ribs formed on the underside and extending to the edge of said surface, thus providing spaced channels between the ribs of substantial depth at said edge, said ribs adapted to cooperate with the earth to form tubular passageways extending to the edge of said basic surface, an axial rib disposed transversely of said first ribs and forming a cross-sectional closure for each of said intermediate channels, and means provided at the closed end of each channel for directing liquid longitudinally through said passageways in order to wash laterally away the earth from under said construction.

3. In combination a tunnel section, foundation-al construction supporting plate or other construction having a large basic surface, and having a vertically disposed sidewall, merging with said surface edge, a plurality of substantially flush-top spaced ribs formed on the underside of said sur-

face and extending to said edge, thus providing spaced channels between the ribs of substantial depth at said edge, said ribs adapted to cooperate with the earth to form tubular passageways extending to the edge of said basic surface, and means for directing liquid longitudinally through said passageways in order to wash laterally away the soil from under said construction, the cross sectional areas of the channels decreasing in the direction of the flow of the liquid.

4. In combination, a tunnel section, foundational construction supporting plate or other three-dimensional construction with a large basic surface, a plurality of substantially flush-top spaced ribs formed on the underside and extending to the edge of said surface, thus providing spaced channels between the ribs of substantial depth at said edge, said ribs adapted to cooperate with the earth to form tubular passageways extending to the edge of said basic surface, an axial rib disposed transversely of said first ribs and forming a cross-sectional closure for each of said intermediate channels, and means provided at the closed end of each channel for directing liquid longitudinally through said passageways in order to wash laterally away the earth from under said construction, the cross-sectional areas of the channels decreasing in the direction of the flow of the liquid.

5. In combination with a construction having a large basic surface, a plurality of substantially flush top spaced ribs formed upon said surface thereby forming intermediate channels of substantial depth throughout the entire length of the latter, said ribs adapted to cooperate with the earth surface to form each of said channels into a tubular passageway extending to the edge of said surface, said channels being open on their undersides and decreasing in cross-sectional areas toward said edge, and a plurality of means for directing liquid longitudinally through each of said passageways in the direction of decreasing cross-sectional area to wash laterally away the earth from under said construction.

6. In combination with a construction having a large basic surface with sidewalls extending upwardly from the edges of said surface, a plurality of spaced ribs formed upon said basic surface thereby providing intermediate channels, each channel having an orifice of a substantial cross-sectional area at the intersection of said basic surface with at least one of said sidewalls, said ribs adapted to cooperate with the earth surface to form each of said channels into a tubular passageway, and means for directing liquid through said passageways to wash laterally away the earth from under said construction.

7. In combination with a construction having a large basic surface with sidewalls extending upwardly from the edges of said surface, a plurality of spaced ribs formed upon said basic surface thereby providing intermediate channels, each channel having an orifice of a substantial cross-sectional area at the intersection of said basic surface with at least one of said sidewalls, said ribs adapted to cooperate with the earth surface to form each of said channels into a tubular passageway, a second rib disposed trans-

versely of said first ribs and forming a cross-sectional closure for each of said channels, and means for directing liquid through said passageways to wash laterally away the earth from under said construction.

8. In combination with a construction having a large basic surface with sidewalls extending upwardly from the edges of said surface, a plurality of spaced ribs formed upon said basic surface thereby providing intermediate channels, each channel having an orifice of a substantial cross-sectional area at the intersection of said basic surface with at least one of said sidewalls, said ribs adapted to cooperate with the earth surface to form each of said channels into a tubular passageway, said channels decreasing in cross-sectional areas toward the respective orifices, and means for directing liquid through said passageways to wash laterally away the earth from under said construction.

9. In combination with a construction having a large basic surface with sidewalls extending upwardly from the edges of said surface, a plurality of spaced ribs formed upon said basic surface thereby providing intermediate channels, each channel having an orifice of a substantial cross-sectional area at the intersection of said basic surface with at least one of said sidewalls, said ribs adapted to cooperate with the earth surface to form each of said channels into a tubular passageway, a second rib disposed transversely of said first ribs and forming a cross-sectional closure for each of said channels, said channels decreasing in cross-sectional areas toward the respective orifices, and means for directing liquid through said passageways to wash laterally away the earth from under said construction.

10. In combination with a construction having a large basic surface and having a sidewall extending upwardly from the edge of said surface, a rib formed upon said surface, two groups of transverse spaced ribs on said surface and extending respectively from each side of said first rib to said edge, thereby forming intermediate channels between adjacent transverse ribs, each channel having a substantial cross-sectional area at the intersection of said basic surface with the sidewall, said transverse ribs adapted to cooperate with the earth surface to form each of said channels into a tubular passageway extending to said edge, liquid supplying means arranged in each transverse rib on one side of the first named rib and opening into a channel between adjacent transverse ribs on the other side of the first named rib.

11. A construction as set forth in claim 10 wherein the transverse ribs on one side of the first-named rib are positioned respectively opposite the channels on the other side of the first-named rib.

12. A construction as set forth in claim 10 wherein the cross-sectional area of each of said channels decreases in the direction of flow of said liquid.
